UNITED STATES PATENT OFFICE.

ARTHUR G. KINNEY, OF FARGO, NORTH DAKOTA, ASSIGNOR TO THE FARGO FOUNDRY COMPANY, OF FARGO, NORTH DAKOTA, A CORPORATION OF NORTH DAKOTA.

DESIGN FOR A STREET-LAMP POST.

Application filed February 27, 1922. Serial No. 907. Term of patent 7 years.

To all whom it may concern:

Be it known that I, ARTHUR G. KINNEY, a citizen of the United States, residing at Fargo, in the county of Cass and State of North Dakota, have invented a new, original, and ornamental Design for a Street-Lamp Post, of which the following is a specification, reference being had to the accompanying drawing, forming part thereof.

The single view of the drawing is a side elevation of a street lamp post embodying the improved design.

I claim:

The ornamental design for a street lamp post, as shown.

ARTHUR G. KINNEY.
